UNITED STATES PATENT OFFICE.

MATTHEW T. CHAPMAN, OF AURORA, ILLINOIS, ASSIGNOR TO THE AMERICAN WELL WORKS, OF AURORA, ILLINOIS, A CORPORATION OF ILLINOIS.

PUMPING MACHINERY.

1,124,295.

Specification of Letters Patent.

Patented Jan. 12, 1915.

Application filed September 30, 1911. Serial No. 652,062.

To all whom it may concern:

Be it known that I, MATTHEW T. CHAPMAN, a citizen of the United States, residing at Aurora, in the county of Kane and State of Illinois, have invented certain new and useful Improvements in Pumping Machinery, of which the following is a specification, reference being had to the accompanying drawings.

10 This invention relates to pumping machinery and is particularly designed for use in connection with a deep well pump.

My improved pump comprises two plungers located in the well one above the other, 15 adapted to lift the water alternately, the operating rod for one of said plungers being hollow so that the other operating rod may work inside of the first.

It is one of the objects of my invention 20 to provide a new and improved means for causing the upward stroke of each plunger to occupy a greater proportion of the time than does the downward stroke. In this way, for an interval just after one of the 25 plungers has reached its lowermost point, both plungers are moving upward. Thus one plunger begins to move upward with the stream of water before the end of the upward stroke of the other plunger, with 30 the result that the water is forced upward in a continuous stream without being permitted to come to rest. This obviates the necessity for giving the stream of water a fresh start at the beginning of the stroke 35 of each plunger, and thus materially lessens the strain upon the pumping machinery.

Another object of my invention is to provide a new and improved arrangement of parts by which the power is applied directly 40 in line with the plunger-rods so as to avoid any side draft which would cramp the mechanism and make necessary the use of an undue amount of energy for raising a given quantity of water.

45 Another object is the improvement of pumping machinery in sundry details hereinafter pointed out.

The means by which I have accomplished 50 these objects are illustrated in the drawings and hereinafter specifically described. That which I believe to be new is set forth in the claims.

In the drawings:—Figure 1 is a side view of my improved pumping machinery; Fig.

2 is a front view thereof; Fig. 3 is a rear view thereof; Fig. 4 is a top view; Fig. 5 is a side view of the driving crank and the levers operated thereby in a different phase of the operation from that shown in the other drawings, parts of the machine being cut away; Fig. 6 is a view, partly in section, of the crank shaft and driving gear; Fig. 7 is a section taken on line 7—7 of Fig. 6; Fig. 8 is a view, partly in section, showing a modified form of crank shaft and gear; and Fig. 9 is a section on line 9—9 of Fig. 8.

Referring now to Figs. 1 to 7 of the drawings, in which corresponding parts are indicated by like reference characters,—10 indicates a base upon which are mounted standards 11—12 of the frame. 13 indicates a bar mounted in the standards 11—12, journaled upon which, by means of hubs 14—15, are bellcrank levers 16—17. As shown in Fig. 3 the hubs 14—15 are secured together by bolts 18 so that the levers 16—17 swing together upon the bar 13. 19 indicates another bar mounted in the standards 11—12, journaled upon which, by means of a hub 20, is a bellcrank lever 21. The bars 13—19 are rigidly connected to the standards 11—12, serving to brace them relative to each other. Each of the levers 16—17 is provided along its rear edge with a slide-box 22, of any suitable construction, and the lever 21 is provided with a similar slide-box 23. In each of said slide-boxes 22—23 is mounted a slide-block 24 mounted upon the wrist-portion 25 of a crank shaft 26 which is journaled in the standards 11—12 by means of bearings 27—28 concentrically-positioned relative to the axis of rotation of the crank-shaft. 29 indicates a gear, suitably secured to one of the arms of said crank shaft, located concentrically relative to the axis of rotation of the shaft. 30 indicates a shaft, journaled in the standards 11—12, mounted on which is a pinion 31 meshing with the gear 29. 32 indicates a driving pulley keyed or otherwise suitably secured upon the shaft 30.

As best shown in Fig. 4, the forward end of the lever 21 is forked, in each of the arms 33—34 thereof there being secured a pin 35. 36—37 indicate links pivotally connected to the arms 33—34 by means of said pins 35, the lower ends of said links being

pivots secured to a cross-head 38. As best shown in Fig. 2, the cross-head 38 is slidably mounted upon upright guide-rods 39-40 which are mounted at their lower ends in a plate 41 suitably secured to the base 10. 42-43 indicate brace-bars extending from the upper ends of the standards 11-12 to the upper ends of the guide-rods 39-40. 44 indicates a brace-bar connecting the upper ends of the guide-rods 39-40.

As best shown in Fig. 2 the forward ends of the levers 16-17 have pivotally mounted thereon, by means of pins 45-46, links 47-48 which are pivotally connected at their lower ends to a cross-head 49 slidably mounted upon said guide-rods 39-40. As shown in said Fig. 2, the cross-head 38 is connected at its central point, between the links 36-37, with a plunger-rod 50, and the cross-head 49 is connected between the links 47-48 with the plunger-rod 51, the said plunger-rod 51 being hollow, with the plunger-rod 50 working inside thereof.

Referring now more particularly to Figs. 6 and 7 which show the crank shaft and driving gear, it will be seen that the concentrically positioned bearing portions 27-28 and the wrist-portion 25 are formed integrally with the arms 52-53, to the latter of which the gear 29 is secured by bolts 54. A stud 55 extends from the outer face of the crank arm 53, passing through a suitable opening in one of the spokes of the gear 29, a nut 56 being screw-threaded thereon. 57 indicates the upper end of the well-tube connecting-head, in which is mounted a stuffing box 58 carried by a plate 58^a. 59 indicates an oil-cup mounted on the stuffing-box 58 surrounding the outer plunger-rod 51. 60 indicates a large pipe leading from one side of the well-tube connecting-head 57 for delivering the water as desired.

With the driving pulley 32 rotating in the direction indicated by the arrow in Figs. 1 and 2, the pinion 31 and the gear 29 will be driven as indicated by the arrows thereon in Fig. 5. As shown in said Fig. 5 the line A-B joining the center of the wrist-portion 25 and the center of the bar 19 is at right angles to the line A-O joining the center of said wrist-portion 25 to the axis of rotation of the crank shaft, and consequently the lever 21 is at its highest point. When the crank has reached the position indicated by the line O-C which is perpendicular to the line B-C, the lever 21 will have reached its lowest point. Likewise when the crank reaches the position indicated by the line O-D which is at right angles to the line D-E passing through the center of the bar 13, the lever 16 will have reached its highest point. When thereafter the crank reaches the position indicated by the line O-F which is perpendicular to the line F-E,

the lever 16 will have reached its lowest point. In the construction shown, each of the angles A-O-C and F-O-D is approximately 125°. It is therefore seen that each of the levers 16-17 and 21 is moving upward 235/360 of the time and moving downward only 125/360 of the time. While the crank is moving from the position indicated by the line O-F to that indicated by the line O-A, the levers 16-17 and 21 are all moving upward, as is also the case when the crank moves from the position indicated by the line O-C to the position indicated by the line O-D. Inasmuch as one plunger-rod is started upward before the other plunger-rod has reached its highest point, it will be seen that the stream of water is not permitted to come to rest at any time during the operation of the pump, one plunger beginning to act before the other plunger ceases its operative stroke. This expedient serves to lessen very materially the strain upon the pumping mechanism as a whole as compared with that upon a pump in which the stream of water comes to a rest at the end of each operative stroke.

By the provision of the two levers 16-17 acting together upon the plunger-rod 51, the action is direct without any side thrust or side strain upon the mechanism. By the provision of the vertical guides and cross-heads by which the plunger-rods are connected to the levers 16-17 and 21, the effective pull upon the plunger-rods is in a direct vertical line.

In Figs. 8 and 9, which show a modification of the shaft and gear, the corresponding parts are indicated by the same reference numerals as in Figs. 6 and 7, but with the addition of an exponent "a." In the construction here shown the arm 61 is made broader than the arm 53 and is secured at both ends by bolts 62 to the gear 29^a. The concentrically positioned bearing at that end of the shaft to which the gear 29^a is attached is made separate from the arm 61 in the form of an axle 63. By this construction the assembling of the parts is more easily accomplished.

Referring to Figs. 1 to 5, 64 indicates bolts which pass through the standards 11-12. 65 indicates spacing blocks in the form of washers placed upon the bolts 64 between the standards. The tightening of the bolts draws said standards and spacing blocks together for holding the frame rigid.

What I claim as my invention and desire to secure by Letters Patent is,—

1. In a pump, the combination of two levers adapted to rock about a common axis, a plunger-rod, means for connecting said plunger-rod between the ends of said levers, a straight pin having a sliding connection with both of said levers, and means for moving said pin about an axis parallel with the

axis upon which said levers are mounted for actuating said levers in unison to reciprocate said plunger-rod.

5 2. In a pump, the combination of two levers adapted to rock about a common axis, a plunger-rod, means for connecting said plunger-rod between the ends of said levers, and a crank having a straight wrist which operates upon said levers for actuating them in unison to reciprocate said plunger-rod.

10 3. In a pump, the combination of two bell-crank levers adapted to rock about a common axis, a plunger-rod, means for connecting said plunger-rod between one arm of one of said levers and the corresponding arm of the other lever, a straight pin having a sliding connection with the other arms of said levers, and means for revolving said pin about an axis parallel with the axis upon which said bell-crank levers are mounted for actuating said levers in unison to reciprocate said plunger-rod.

15 4. In a pump, the combination of two bellcrank levers adapted to rock about a common axis, a plunger-rod, means for connecting said plunger-rod between one arm of one of said levers and the corresponding arm of the other lever, and a crank having a straight wrist which operates upon the other arms of said two levers for actuating said levers in unison to reciprocate said plunger-rod.

20 5. In a pump, the combination of two bell-crank levers adapted to rock about a common axis, one arm of one of said levers and the corresponding arm of the other lever being provided with slide-boxes, a crank having a straight wrist which operates in said slide-boxes to reciprocate the other arms of said levers in unison up and down, a plunger-rod, and means for connecting said plunger-rod between said last-named arms of said levers.

25 6. In a pump, the combination of a frame, a plurality of bellcrank levers mounted thereon on parallel axes one above the other with one arm of each lever pointing in its intermediate position toward the axis upon which the other lever is mounted, means operating upon both of said arms for actuating said levers to swing the other arms in opposite directions, and a plurality of plunger rods connected to said last-named arms respectively.

30 55 7. In a pump, the combination, of a frame, a plurality of bellcrank levers mounted thereon on parallel axes one above the other with one arm of each lever pointing in its intermediate position toward the axis upon which the other lever is mounted, a crank operating upon both of said arms for actuating said levers to swing the other arms in opposite directions, and a plurality of plunger rods connected to said last-named arms respectively.

8. In a pump, the combination of a frame, a plurality of bellcrank levers mounted thereon on parallel axes one above the other with one arm of each lever pointing in its intermediate position toward the axis upon 70 which the other lever is mounted each of said arms being provided with a slide-box, a crank operating in said slide-boxes adapted to swing the other arms of said levers in opposite directions, and a plurality of plunger rods connected to said last-named arms respectively.

9. In a pump, the combination with a lever, a crank having a straight wrist which has a sliding connection with said lever for reciprocating the lever, two plunger-rods located in the plane of said lever, and means for operatively connecting said lever with one of said plunger-rods, of two oppositely-disposed levers adapted to be reciprocated 85 in unison by said straight crank wrist, one of said last-named levers being on either side of said first-named lever, and means for operatively connecting the free ends of said last-named levers with the other of said 90 plunger-rods.

10. In a pump, the combination with a bellcrank lever, a crank having a straight wrist which has a sliding connection with one arm of said lever whereby by rotation of 95 the crank said lever is reciprocated, two plunger-rods located in the plane of said lever, and means for operatively connecting the free arm of said lever with one of said plunger-rods, of two oppositely-disposed 100 bellcrank levers adapted to be reciprocated in unison by said straight crank wrist, one of said levers being on either side of said first-named lever, and means for operatively connecting the free arms of said last-named 105 levers with the other of said plunger-rods.

11. In a pump, the combination with a bellcrank lever, a crank having a straight wrist which has a sliding connection with one arm of said lever whereby by rotation of 110 the crank said lever is reciprocated, two plunger-rods located in the plane of said lever, a vertical guide, a slide-block connected to one of said plunger-rods and adapted to be reciprocated up and down on 115 said guide, and means for operatively connecting the free arm of said lever with said slide-block, of two oppositely-disposed bellcrank levers adapted to be reciprocated in unison by said straight crank wrist, one of 120 said levers being on either side of said first-mentioned lever, a second slide-block connected to the other of said plunger-rods and adapted to be reciprocated up and down on said guide, and means for operatively connecting the free arms of said last-named 125 levers with said last-named slide-block.

12. In a pump, the combination with a bellcrank lever, a crank having a straight wrist which has a sliding connection with 130

one arm of said lever whereby by the rotation of the crank said lever is reciprocated, two plunger-rods located in the plane of said lever, two vertical guide-rods on opposite sides of said plunger-rods, two cross-heads adapted to slide up and down on said guide-rods, each of said cross-heads being connected to one of said plunger-rods, and links connecting the free arm of said lever with 10 one of said cross-heads, of two oppositely-disposed bellcrank levers adapted to be reciprocated in unison by said straight crank wrist, one of said levers being on either side of said first-named lever, and links connecting 15 the free arms of said last-named levers with the other of said two cross-heads.

13. In a pump, the combination of two levers mounted on a fixed axis, means connecting said two levers so that they swing in 20 unison, a third lever positioned between said first-named two levers and mounted on a fixed axis parallel with that upon which said first-named levers are pivoted, two plunger-rods located in the plane of the central lever, 25 means operatively connecting one of said plunger-rods to said central lever, means operatively connecting the other of said plunger-rods to said two levers, and a crank having a single straight wrist adapted to 30 actuate all of said levers to reciprocate the plunger-rods in opposite directions.

14. In a pump, the combination of three levers each provided with a slide-box, a crank the wrist of which works in said slide-boxes for reciprocating said levers, the outside levers being swung in unison, and the intermediate lever being swung for a part of the time in the same direction with the outside levers but for a greater part of the time 40 in the opposite direction, and plunger-rods one operatively connected to said two outside levers and the other operatively connected to said intermediate lever.

15. In a pump, the combination of three levers each provided with a slide-box, a crank the wrist of which works in said slide-boxes for reciprocating said levers, the outside levers being swung in unison and the intermediate lever being swung for a part of the time in the same direction with the outside levers but for a greater part of the time in the opposite direction, two plunger-rods, 50 connections between said two outside levers and one of said plunger-rods, connections between said intermediate lever and the other of said plunger-rods, and means adapted to cause said connections to move in a vertical line whereby there is no side strain upon the plunger-rods as said levers are reciprocated.

16. In a pump, the combination of two levers, means connecting said two levers so that they swing in unison, a third lever positioned between said first-named levers, each of said levers being provided with a slide- 65 box, a crank adapted to operate in said three

slide-boxes to reciprocate said levers, two plunger-rods located in the plane of the central lever, means operatively connecting one of said plunger-rods to said central lever, and means operatively connecting the other of said plunger-rods to the said two levers. 70

17. In a pump, the combination of two levers, means connecting said two levers so that they swing in unison, a third lever positioned between said first-named two levers, 75 each of said levers being provided with a slide-box, a crank located between the two axes upon which said levers are pivoted adapted to operate in said three slide-boxes to reciprocate said levers, two plunger-rods located in the plane of the central lever, means operatively connecting one of said plunger-rods to said central lever, and means operatively connecting the other of said plunger-rods to the said two levers. 80

18. In a pump, the combination of two levers, means connecting said two levers so that they swing in unison, a third lever positioned between said first-named two levers, 85 each of said levers being provided with a slide-box the central longitudinal line of which passes through the axis upon which the lever swings, a crank journaled midway between said two axes adapted to operate in said three slide-boxes to reciprocate said levers, two plunger-rods located in the plane of the central lever, means operatively connecting one of said plunger-rods to said central lever, and means operatively connecting the other of said plunger-rods to the said two levers. 90

19. In a pump, the combination of two levers, means connecting said two levers so that they swing in unison, a third lever positioned between said first-named two levers, 100 two plunger-rods located in the plane of the central lever, means operatively connecting one of said plunger-rods to said central lever, and means operatively connecting the other of said plunger-rods to the said first-mentioned two levers.

19. In a pump, the combination of two levers, means connecting said two levers so

that they swing in unison, a third lever positioned between said first-named two levers, 105

two plunger-rods located in the plane of the central lever, means operatively connecting one of said plunger-rods to said central lever, and means operatively connecting the other of said plunger-rods to the said first-mentioned two levers, and a single crank operatively connected to said levers adapted to 110 swing them up and down.

20. In a pump, the combination of two levers mounted on a fixed axis, means connecting said two levers so that they swing in

unison, a third lever positioned between said first-named two levers and mounted on a

fixed axis parallel to that upon which said

first-named levers are pivoted, a single crank journaled midway between said two axes operatively connected to said levers adapted to

swing them up and down, two plunger-rods located in the plane of the central lever, means operatively connecting one of said

plunger-rods to said central lever, and means operatively connecting the other of said plunger-rods to the said first-mentioned

two levers. 120

20. In a pump, the combination of two levers mounted on a fixed axis, means connecting said two levers so that they swing in

unison, a third lever positioned between said first-named two levers and mounted on a

fixed axis parallel to that upon which said

first-named levers are pivoted, a single crank journaled midway between said two axes operatively connected to said levers adapted to

swing them up and down, two plunger-rods located in the plane of the central lever, means operatively connecting one of said

plunger-rods to said central lever, and means operatively connecting the other of said plunger-rods to the said first-mentioned

two levers. 125

21. In a pump, the combination of a base, 130

- two standards rising therefrom, two transverse bars connected to said standards adapted to hold the same rigid relative to each other, two levers mounted on one of said transverse bars, a third lever mounted on the other of said transverse bars adapted to swing between said first-named two levers, two plunger-rods, means for connecting one of said plunger-rods to said two levers mounted on one of said transverse bars, and means for connecting the other of said two plunger-rods to the intermediate lever mounted on the other of said transverse bars.
22. In a pump, the combination of three levers each provided with a slide-box, a crank the wrist of which works in said slide-boxes for swinging said levers in opposite directions, and plunger-rods operatively connected to said levers.
23. In a pump, the combination of three levers, operated by sliding blocks driven by a crank, one of said levers being operated between the other two levers for moving pump rods in opposite directions.
24. In a pump, the combination of three levers operated by sliding blocks driven by a crank, one of said levers being operated between the other two levers for moving pump rods in opposite directions in part of the revolution of the crank and in the same direction in another part of the revolution of the crank.
25. In a pump, the combination of three levers operated by sliding blocks driven by a crank, one of said levers being operated between the other two levers for moving pump rods in opposite directions in part of the revolution of the crank and in the same direction in another part of the revolution of the crank.
26. In a pump, the combination of three levers operated by sliding blocks driven by a crank, one of said levers being operated between the other two levers for moving pump rods in opposite directions in part of the revolution of the crank and in the same direction in another part of the revolution of the crank, and means for holding the pump rods in vertical alinement.
27. In a pump, the combination of a base, two standards rising therefrom, two transverse bars connected to said standards adapted to hold the same rigid relative to each other, two levers mounted on one of said transverse bars, a third lever mounted on the other of said transverse bars adapted to swing between said first-mentioned two levers, each of said levers being provided with a slide-box, a single crank wrist operating in the slide-box of said three levers adapted to reciprocate said levers, two plunger-rods located in the plane of said intermediate lever, means for connecting one of said plunger-rods to the two levers mounted on one of said transverse bars, and means for connecting the other of said plunger-rods to the intermediate lever mounted on the other of said transverse bars.
